APPARATUS FOR TENSIONING AN ARM

Rafe C. Chaffin, Los Angeles, Calif.

Application March 25, 1946, Serial No. 656,996

6 Claims. (Cl. 128—84)

1

This invention has to do with apparatus for tensioning an arm, it being a general object of the invention to provide apparatus to effectively tension parts of a human arm and more specifically the forearm or parts in the region of the forearm.

In the case of fractures occurring in the forearm or in the region of the fore-arm and in the case of certain other injuries or disturbances at this part or region of the body it becomes necessary or desirable to apply tension between the elbow and the hand or, in other words, in the fore-arm. The most common example of such a situation is where a complete break or fracture necessitates the application of considerable tensile stress to the forearm in order to bring the fractured parts in proper alignment for setting.

In accordance with the method ordinarily followed in such a situation the upper arm is held by any improvised means and a hold is taken on the wrist and tension applied without any particular care or attention being given to the position of hand or wrist or to the matter of circulation in these parts.

It is a general object of my present invention to provide a simple, practical, easily operated apparatus applicable to a human arm to effectively hold or anchor the upper arm and to apply tension by gripping the hand, or the hand and wrist, while holding the hand flat and parallel with the forearm and without materially impairing circulation to the hand.

Another object of my invention is to provide apparatus of the general character hereinabove referred to which involves few simple easily operated parts which combine to provide an adjustable device that will accommodate hands of various sizes and shapes. The apparatus that I have provided is quickly adjustable to various widths so that it will effectively accommodate a wide variation in hands.

It is another object of my invention to provide apparatus of the general character referred to wherein there is a grip applicable to the hand or the wrist and hand which grip involves a flat hand plate combined with a strap so that the hand plate supports the hand flat and parallel with the forearm when strain or tension is applied through the strap.

Another object of my invention is to provide apparatus of the general character hereinabove referred to which is not only readily adjustable to accommodate hands of various sizes, but which is also very quickly applicable to a hand and

which is such that there is little or no possibility of the apparatus being mis-used or mis-applied.

The various objects and features of my invention will be fully understood from the following detailed description of typical preferred forms and applications of the invention, throughout which description reference is made to the accompanying drawings, in which:

Fig. 1 is a view illustrating the manner in which the apparatus that I have provided is used to tension a forearm. Fig. 2 is an enlarged side elevation of a part of the anchor element of the apparatus. Fig. 3 is a plan view of the parts shown in Fig. 2, being a view taken as indicated by line 3—3 on Fig. 2. Fig. 4 is an enlarged side elevation of a portion of the grip element of the apparatus. Fig. 5 is a top plan view of the part shown in Fig. 4. Fig. 6 is an enlarged detailed sectional view taken as indicated by line 6—6 on Fig. 5. Fig. 7 is a view similar to Fig. 5 showing a modified form of the invention. Fig. 8 is a side elevation of the structure shown in Fig. 7. Fig. 9 is a detailed sectional view taken as indicated by line 9—9 on Fig. 7. Fig. 10 is a detailed sectional view taken as indicated by line 10—10 on Fig. 7. Fig. 11 is an enlarged sectional view as taken by line 11—11 on Fig. 7. Fig. 12 is a detailed sectional view taken as indicated by line 12—12 on Fig. 11. Fig. 13 is a plan view of part of the device shown in Fig. 1, and Fig. 14 is a side elevation of the mechanism shown in Fig. 13.

The apparatus that I have provided includes or involves, generally, three units or elements, one of which I will term the anchor element A, another I will term the grip element B and the other I will term a tensioning means C. The anchor element A is adapted to be applied to the upper arm or arm proper adjacent the elbow to hold it back or against forward movement when the apparatus is being used, while the grip B is applied to the hand, or hand and wrist preferably, while the forearm is in a forward or horizontal position, substantially as shown in Fig. 1 of the drawings. The tensioning means C connects to the grip B and is operable to apply tension or traction so that tensile strain is set up in the forearm or in the region thereof.

The anchor element A that I have provided involves, generally, a bearing plate 10, a fastening device 11, and a strap 12 connecting the plate and fastening device. In practice I prefer to make the anchor element A simple and free of complicated parts or constructions, and I prefer to proportion it so that it will accommodate most any upper arm.

2

The bearing plate 10 may be formed of a metal plate which in the blank or initial form is substantially round and which is bent laterally of its plane so that it is substantially U-shaped and has a round forward portion 13 to bear against the forward side of the upper arm and has rearwardly projecting spaced flanges or side parts 14 to extend rearwardly at the inner and outer sides of the arm. In practice it is desirable to curve or deflect the lower portion of the part 13 as at 13^a so that it curves forward to have comfortable bearing on the arm immediately adjacent the elbow.

The fastening device may be any suitable part, mechanism or device by which the element A is secured as to a fixed support or the like. In the drawings I have shown a simple ring forming the fastening device 11, which ring can be applied to a hook or the like or can be tied by any suitable member to the desired support.

The strap 12 is preferably a flexible strap or belt either of fabric or leather or like material, and in the preferred form of the invention it has spaced side parts 15 which extends rearward from the rearwardly extending sides 14 of the bearing plate to the ring 11. I preferably secure the side parts 15 of the strap to the side parts 14 of the bearing plate by suitable rivets 17 or the like, and I preferably connect the forward ends of the side parts 15 of the strap by connecting part 18 which extends around the front of the bearing plate in the manner clearly shown in Figs. 1, 2 and 3 of the drawings. The rear ends of the side parts 15 of the strap may be joined together and to the ring 11 in any suitable manner.

The grip B involves, generally, a hand plate 20 on which the hand bears, and a retaining means 21 in connection with the hand plate for retaining the hand on the plate, and a strap 23 connecting the means C and the plate and having a portion to engage the hand or wrist to retain on the plate.

The hand plate that I have provided may be varied considerably in form and construction and, essentially, it involves an elongate flat plate with a wide center portion 25 to support the wide part of the hand, a narrow forward portion 26 to support the fingers and thumb, and a narrow rear portion 27 to support the wrist or the forward end portion of the forearm.

I may make the hand plate adjustable and to do this I make it sectional or, in other words, I divide it longitudinally so that it involves two overlapping sections X and Y. The sections X and Y are preferably formed of sheet metal or the like and their inner or adjacent edge portions overlap in the manner clearly shown in Figs. 5 and 6 of the drawings.

When the hand plate is made sectional as I have just described I guide the sections relative to each other so that they can be moved in and out to vary the width of the hand plate. The particular guide means that I have shown in the drawings involves spaced guide rods 30 on one of the plates slidably fitting guide blocks 31 on the other plate. In the particular case illustrated I have shown two guide rods spaced below the two plate sections and extending transversely of the hand plate. Each rod is rigidly supported in connection with one of the plates by a post 32 secured to the plate section by welding or the like. The blocks 31 that guide the rods 30 are made fast to the other plate section and have bores or openings 33 that slidably carry the rods.

In accordance with the preferred form of my invention I provide means 35 for locking the sections of the hand plate in the desired adjusted position. The particular means illustrated involves a grip ring 36 surrounding each rod 30 and each grip ring is carried by a support or carriage 37 so that it can be tilted into gripping engagement with the rod that it surrounds by means of a spring 38 surrounding the rod. The grip rings 36 are tilted in a direction so that the sections X and Y of the hand plate can be readily separated or pulled apart and they serve to grip the rods and lock them so that they prevent the plate sections being moved together.

When the structure is provided with a lock means such as I have described I preferably include in the construction means operable to release the locks or lock means. In the case illustrated in the drawings I provide a cam 50 at each lock ring and I support the cams by means of a tie rod 51 which can be shifted so that the cams engage the lock rings and tilt them against the action of the springs 38. The rod 51 extends lengthwise of the hand plate and is guided for reciprocation lengthwise of the hand plate in suitable guide brackets 52. In practice I can operate the cams or the rod 51 carrying the cams in any suitable manner. In the particular case illustrated I operate the rod 51 by means of a bell crank which has one arm 55 arranged to form a lever that can be conveniently depressed by the operator and the other arm 56 engaged through an opening provided in an extension 57 of the rod 51. The bell crank is carried on a pivotal support 58 and is preferably located at the under side of the hand plate and adjacent one end thereof, for instance, near the inner end thereof, as shown in the drawings.

With the construction just described the springs 38 acting on the grip rings normally hold the mechanism in position so that the rods 30 are gripped whenever there is a tendency to move them into the openings 33 but the rods are always free to be withdrawn to widen the hand plate. When it is desired to collapse the hand plate or move the sections thereof in so that the hand plate is made narrower it is merely necessary for the operator to depress the hand lever 55 which causes movement of the rod 51 so that the cams 50 tilt the grip rings 36 against the resistance of the springs 38, freeing the rods 30 so that they can be moved at will.

The retaining means 21 provided to retain the forward portion of the hand is carried by the hand plate to hold the forward or finger portion 55 of the hand flat on the plate. The means 21 preferably involves a strap secured to the edge portions of the two plate sections X and Y so that it extends or loops over the hand plate. In the preferred form of the invention as shown in the drawings the strap involves two sections 60 and 61 joined by an adjusting means or buckle 62 so that it can be tightened in the desired manner over the hand. The strap sections 60 and 61 are secured to suitable brackets 63 at opposite edges of the hand plate. In practice the strap sections 60 and 61 can be made fast to the brackets 63 as shown in the drawings. I preferably locate the strap construction just described lengthwise of the hand plate so that it extends across the back of the hand at or near the fingers so that the fingers of the hand are effectively retained flat on the plate.

The strap 23 of the grip element B has a loop portion 70 that extends transversely across the

rear portion of the hand plate and has side portions 71 that extend forward from the loop portion to be guided by the hand plate and to finally connect to the means C.

The loop portion extends transversely over the hand plate so that it grips in the region of the wrist or just behind the point where the thumb joins the hand so that it occurs at a point adjacent the widest part of the hand and when tightened effectively prevents slippage of the hand from the plate. In the form of the invention shown in the drawings the strap is guided by guide brackets 75 projecting from opposite edge portions of the hand plate at or close to the point where the wide portion 25 of the plate joins the narrow rear portion 27 thereof. The brackets 75 may be simple projections having openings 76 that slidably pass the strap. The side portions 71 of the strap extend forward from the brackets 75 at the under side of the plate to the forward end of the plate where they are engaged by guide brackets 77. The guide brackets 71, as shown in the drawings, may be downwardly turned flanges at the forward ends of the plate sections, which flanges have openings 78 slidably passing the strap. The side portions 71 of the strap extend forward from the hand plate and connect together or to a fastener 82 so that the fastener is connected to the hand plate by means of the side portions 71 of the strap.

The tensioning or traction means C that I have provided connects to the strap portions 71 which I have shown connected together and carrying a suitable hook or fastener 82 which facilitates their connection to the means C. The means C involves, generally, a block and tackle mechanism which I have shown as including a main block R and a traveling block S. The traveling block in the case shown involves spaced sheave plates 90 between which I mount sheaves 91 and one of the plates 90 has an extension 92 which may be provided with a ring 93 to receive the hook 82 or the strap extension itself, as the case may be.

The main block R involves a plurality of sheave plates 94 between which sheaves 95 are arranged and one of the plates has an inner extension 96 to which one end 97 of an operating line L is attached. The plate having extension 96 has an outer extension 98 that may be provided with a ring 99 or the like to facilitate connection to an anchoring line or tie 100 as shown in Fig. 1 of the drawings. The operating line L extends from the point where it is anchored to the main block R as above described over a pulley or traveling block and from that point it is suitably run back and forth over or between the pulleys of the two blocks so that it has an extending or projecting end 101 that can be gripped for operation. A lock means is provided in the mechanism just described so that when the line has been operated to draw the blocks toward each other the desired tension can be maintained at the part to be set. The lock means that I have shown involves a fixed abutment pin 103 in the main block R and a lock cam 104 on a pivot pin 105 to be operated by a handle 106 so that it can be turned into gripping engagement with the line L in the manner that will be apparent from an examination of Figs. 13 and 14 of the drawings.

In using the apparatus that I have provided the anchor element A is preferably employed to hold or retain the upper arm or arm proper and it is preferably applied to this part as close

as possible to the elbow in a manner such as is shown in the drawings. The retaining means 21 is loosened or released and the strap 23 is manipulated so that the loop portion 70 is large enough to allow the hand to be freely passed forward over the plate to the desired position, the plate being adjusted to the desired width. If it is desired to widen the plate it is merely necessary to pull the sections X and Y apart, whereas if it is desired to make the plate narrower this can be done when the lever 55 is operated, as above described. With the hand on the hand plate in the manner illustrated in the drawings and with the loop 70 of the strap 23 engaged over the hand adjacent the wrist or immediately behind the side portion of the hand and the means 21 made tight to retain the fingers or forward portion of the hand tight on the plate, tension can be applied to the strap 23.

When tension or traction is applied to the strap 23, as for instance through the hook 82, or through the means C, the loop 70 is drawn tight over the hand keeping the wrist portion tight against the plate and the strap or retaining means 21 continues to hold the finger or forward portion of the hand tight on the plate. If the strain or tension is applied in the proper direction, for instance in a direction such as is indicated by the arrow in Fig. 1, the forearm, or parts in the region thereof, is tensioned while the hand is held flat and in a comfortable position, and there is no binding action to interfere with proper circulation to the hand.

It will be apparent that by employing the tensioning means C that I have provided the operator can very easily manipulate the available or free end 101 of the line L so that the blocks R and S are moved together with substantial force. In fact, the operator has a very marked mechanical advantage so that it is a very simple matter to obtain a high degree of tension. It is significant that substantial tension or force of the kind desired can be obtained easily as it makes it possible to use the apparatus without tugging or twisting or putting undue strains on the limb being manipulated, and likewise it applies all of the tension in the desired direction.

In the form of the invention shown in Figs. 7 to 12, inclusive, the hand plate instead of being adjustable as I have described above, is a solid or rigid plate 20^a preferably shaped and proportioned substantially as shown in the drawings. In this form of the invention the retaining means 21^a may be substantially the same as the retaining means above described. In detail the retaining means 21^a involves two strap sections 60^a and 61^a the ends of which are made fast to anchors 63^a slidably carried by the plate 20^a. The anchors have stems 63^b that slide in slots 63^c extending transversely of the plate 20^a and heads 63^d are provided on the stems to retain the anchors in place on the plate. A buckle 62^a joins the strap sections the same as in the form 65 of the invention first described. Through the construction that I have just described the retaining means is simple and yet will accommodate hands of various sizes or widths since the anchors which hold the strap sections can be moved in and out in the slots 63^c to the desired positions.

In the form of the invention that I am now describing the strap 23^a instead of having two divided parts projecting to connect with the means C has a single connecting part or lead 80

from which side portions 71^a branch to diverge beneath the plate 20^a and then extend up and join together above the plate to form a loop portion 70^a. The portions of the strap that extend across the bottom of the plate and then up and across to the top of the plate to form the loop are not carried by brackets as in the case of the invention first described, but in guide slots 76^a which correspond, generally, to the openings 76 in the brackets 75 above described. The slots or openings 76^a are formed or defined by guide bars 76^b which cooperate with the plate and are secured thereto by posts 76^c so that they are spaced somewhat below the plate and at a suitable angle relative thereto and act with the plate in effectively guiding the strap. In this form of the invention the lead 80 beneath the plate is guided relative to the plate by a cross-bar 80^a mounted a suitable distance below the plate by means of suitable posts 80^b.

In carrying out the form of the invention shown in Figs. 7 to 12, inclusive, it is desirable to form the parts that I have above described so that the slots 76^a are not parallel or transverse of the plate but are angularly related, as shown in the drawings, and it is preferred to make them considerably longer than the strap is wide in order to allow for suitable adjustment in the width of the looped portion 70^a of the strap.

It will be apparent from the foregoing description that the form of the invention that I have shown in Figs. 7 to 12, inclusive, can be used with the operating means C as I have above described, it being apparent how the extension 80 of the strap in the form of the invention last described may be connected to the means C in the same manner as the strap extension in the form of the invention first described.

From the foregoing description it will be readily understood how I have provided a structure that can be easily and quickly applied and that the construction is such that no great skill or experience is necessary for its proper use.

Having described only a typical preferred form and application of my invention, I do not wish to be limited or restricted to the specific details herein set forth, but wish to reserve to myself any variations or modifications that may appear to those skilled in the art and fall within the scope of the following claims.

Having described my invention, I claim:

1. Apparatus of the character described including, an anchor applicable to the upper arm of a person, and a grip applicable to the hand of the person, the anchor including a bearing plate into which the forward side of the upper arm bears and a strap carrying the plate, and the grip including a hand plate supporting the hand in a flat position parallel with the forearm, a single strap carrying the plate and having a head portion projecting therefrom and having a portion engageable over the hand to hold it to

the plate, and means retaining the hand on the plate.

2. An anchor device of the character described including a rigid bearing plate U-shaped to have a curved part to support the forward side of an upper arm and having spaced rearwardly extending side parts, and a strap carrying the plate having side parts attached to the side parts of the plate and extending rearwardly from the side parts of the plate.

3. A grip of the character described including a hand plate, and a strap engaged with the plate having a loop portion extending over the rear portion of the plate and side parts extending forward from the loop portion under the plate the strap having a lead portion projecting from the forward end of the plate.

4. A grip of the character described including a hand plate, and a strap engaged with the plate having a loop portion extending over the rear portion of the plate, the strap extending forward from the loop portion under the plate and having a lead portion projecting from the forward end of the plate, the plate having guides 25 at its edges from which the loop portion extends and at its forward end portion where the lead portion of the strap projects from the plate.

5. A grip of the character described including a substantially flat plate to be engaged by the 30 palm and fingers of a hand, and a strap engaged with the plate having a hand engaging loop portion extending over the rear portion of the plate and extending forward from the loop portion under the plate to project from the forward end of the plate, the plate including two overlapping longitudinal sections movable relative to each other to vary the width of the plate.

6. A grip of the character described including a hand plate, and a strap engaged with the 40 plate having a loop portion extending over the rear portion of the plate and extending forward from the loop portion under the plate to project from the forward end of the plate, the plate including two longitudinal sections movable relative to each other to vary the width of the plate, means locking the sections against relative movement, and cam means operable to release the locking means.

RAFE C. CHAFFIN.
